UNITED STATES PATENT OFFICE.

AXEL JOHNSON, OF OAKLAND, CALIFORNIA.

QUICK-ACTING THERMOSTAT.

Application filed November 19, 1923. Serial No. 675,452.

To all whom it may concern:

Be it known that I, AXEL JOHNSON, a citizen of the United States, residing at Oakland, in the county of Alameda and

5 State of California, have invented certain new and useful Improvements in Quick-Acting Thermostats, of which the following is a specification.

Thermostats as heretofore generally manufactured have been constructed to accomplish a relatively slow break between the electrical contact points of the circuit to be controlled, resulting in an arc being formed on the making and breaking of the 15 points which in time causes the pitting of the points and an inefficient completion of the circuit when the contacts are closed.

The present invention relates to a thermostat designed particularly for controlling 20 electrical circuits whereby in its use a quick breaking and completion of the circuit is made, overcoming the arcing between the contact points and consequently overcoming the burning out and pitting of the contact 25 points. One of the objects of this invention is to provide a thermostat controlling an electric circuit by the use of which renewal of the contact points is reduced to a minimum; one wherein the contact points are 30 positively retained in opened or closed position when moved thereinto by the action of the thermostat, one in which the adjustment of the thermostat can be readily varied and wherein the tension of the means for 35 accelerating the movement of the contact lever may be varied.

With the above mentioned and other objects in view, the invention consists in the novel construction and combination of parts 40 hereinafter described, illustrated in the accompanying drawings, and set forth in the claims hereto appended, it being understood that various changes in the form, proportion, size and minor details of construction 45 within the scope of the claims may be resorted to without departing from the spirit or sacrificing any of the advantages of the invention.

Fig. 1 is a view in side elevation, of the preferred embodiment of my invention illustrating the parts in a position with the contact finger closed.

Fig. 2 is a view similar to Fig. 1 illustrating the reverse side of the invention and with the contact fingers in open position.

Fig. 3 is a view in front elevation.

Fig. 4 is a view in detail in longitudinal section of the trigger movement accelerating means illustrating the plunger in contact with one face of the trigger end incline.

Fig. 5 is a view similar to Fig. 4 illustrating the trigger plunger in contact with the opposite face of the trigger end incline.

Fig. 6 is a transverse sectional view 65 taken on the line 6—6 of Fig. 1.

In the drawings, wherein like characters of reference indicate corresponding parts throughout the several views, 1 indicates a base preferably of insulating material to 70 which is secured the flange portion 2 of a supporting plate 3. The flange 2 of the plate 3 is secured to the base by one or more bolts 4, one of which serves as a binding post for attaching an electric conductor. Secured to 75 the base at a point removed from the plate 3 by a nut 5 is a stationary contact member 6, the securing nut affording a binding post for the attachment of an electrical conductor. Fulcrumed at one end as at 7 to the 80 plate 3 is a movable contact lever 8 the end 9 of which is adapted for movement into and out of contact with the stationary contact member 6. To operate the lever 8 I employ an element referred to herein as 85 a trigger 10 fulcrumed at one end as at 11 to the plate 3 and the same is provided with a recess 12 into which extends the angularly bent finger portion 13 projecting laterally from one edge of the movable contact lever 90 8. I provide a free movement between the edges of the recess 12 and the opposite faces of the member 13 which permits of a movement of the trigger 10 prior to its operating the lever 8. Integral with the trigger 10 95 is formed an arm 14 extending preferably parallel with the contact lever 8 and at its end the same carries an adjustable headed screw member 15 adapted to be received within the slotted opening 16 in the free 100 end of a thermostat bar 17 of any well-known construction, the bar being curved at its lower end and anchored as at 18 to the plate 3. The thermostat bar is adapted to impart pivotal movement to the trigger 105 10 prior to the wall of the recess 12 engaging one face of the member 13 and the adjustment of the apparatus in such that the trigger is preferably in the center of its arcuate movement in either direction prior 110 to imparting any movement to the lever 8.

To accelerate the movement of the trig-

ger after the same has been moved by the thermostat bar 17 a predetermined distance, I employ an accelerating means, the present embodiment of which is illustrated as a reciprocating plunger 19 having a V-shaped lower end 20 which engages the opposite inclined faces of an inverted V-shaped upper end 21 formed on the trigger 10, this construction being clearly illustrated in Figs. 4 and 5. The plunger reciprocates in a tubular guide 22 and is normally pressed downwardly by a coiled spring 23 surrounding the stem 24 thereof. An adjusting nut 25 at the upper end of the stem 24 and bearing against the upper end of the tubular portion 22 is adapted for varying the operative movement of the plunger 19. A leaf spring 26 having a curved free end 27 disposed to slightly overlie the path of movement of the free end of the member 8 and secured to the base 1 as at 27 is adapted for positively maintaining the movable contact lever 8 in either open or closed position.

The parts of the embodiment illustrated being assembled as in Fig. 1 of the drawings, an increase in temperature sufficient to operate the bar 17, will cause the free end of the bar to swing and this will impart an outward movement to the trigger 10, causing the wall of the inverted V-end 21 of the trigger to ride over one wall of the V end of the plunger 19 until such time as the trigger has completed approximately one-half of its arcuate movement. Up to this time movement has not been imparted to the lever 8, but immediately on the thermostat bar 17 moving the trigger 10 to a point beyond its median line of movement the action of the spring 23 on the plunger 19 will cause the plunger to accelerate the movement of the trigger which in turn will cause a rapid movement from making to breaking position of the contact lever 8. On the cooling of the thermostat bar 17 the movement of the parts in a reverse direction takes place and the movable contact lever 8 is rapidly

closed by the action of the trigger accelerating plunger 19.

On the closing of the movable contact 8, it will be observed that the action of the plunger 19 on the inclined surface of the trigger, will force the extension 28 on the trigger into contact with one edge of the lever 8 and assist in maintaining the lever in contact or circuit closing position.

Having thus described my invention, what I claim as new and desire to protect by Letters Patent of the United States is:—

1. A thermostatic control for electric circuits including a stationary contact and an associated contact lever adapted for pivotal movement to and from said stationary contact, a pivotally mounted trigger, a thermostat operatively connected with the trigger, means co-operating with the trigger for accelerating its movement in either direction after being moved to a predetermined point in said direction by the thermostat, and a loose connection between the lever and trigger whereby accelerated movement is imparted to the trigger prior to the operation of the lever thereby.

2. A thermostatic control for electric circuits including a stationary contact and an associated contact lever adapted for pivotal movement to and from said stationary contact, a pivotally mounted trigger and provided with intersecting bevelled faces, a thermostat for operating said trigger, a spring pressed plunger having intersecting bevelled faces for co-operating with the bevelled faces of said trigger for imparting accelerated movement to the trigger after the same has been moved a predetermined distance by said thermostat, and a loose connection between the trigger and lever whereby accelerated movement is imparted to the trigger prior to the trigger operating the lever.

In testimony whereof I have signed my name to this specification.

AXEL JOHNSON.
